(57) **CLAIM**

The ornamental design for an eyeglasses temple tip, as shown and described.

DESCRIPTION

FIG. 1 is a perspective view of an eyeglasses temple tip showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The broken lines shown in the drawings depict portions of the eyeglasses temple tip in which the design is embodied that form no part of the claimed design.
